RICHARD SALTER, OF CINCINNATI, OHIO, ASSIGNOR TO HIMSELF
AND JOSEPH B. DAVIS, OF SAME PLACE.

Letters Patent No. 88,520, dated March 30, 1869.

IMPROVED GAS-COOLER AND WASHER.

The Schedule referred to in these Letters Patent and making part of the same.

To all whom it may concern:

Be it known that I, RICHARD SALTER, of Cincinnati, in the county of Hamilton, and State of Ohio, have invented a certain new and useful Improved Gas-Cooler and Washer; and I do hereby declare that the following is a full, clear, and exact description of the construction and operation of the same, reference being had to the annexed drawing, making part of this specification, in which the figure is a vertical section of my improved gas-cooler and washer.

It is known that ordinary burning-gas, immediately after leaving the retorts, contains impurities, from which it must be cleansed before it is fit for use.

The purification, or final cleansing of gas is usually done by passing it through dry lime; but, before that is done, there are certain volatile impurities which must be separated from it by condensing them.

It is known that, in order to accomplish the latter purpose, the gas must be kept at a very low temperature, and, while at such low temperature, must come in contact with a large area of surface, upon which the impurities may deposit as they are condensed.

The object of my invention is to accomplish this more effectively than it has heretofore been done, and, for this purpose, I force the gas through the boulders, which are kept constantly cooled with water.

To enable others to use my invention, I shall proceed to describe its construction and mode of operation.

M is a rectangular box.

D is a partition, dividing the box M into two chambers, L and L', and extending from the top to the perforated bottom N. Its joints are all hermetical.

B and B' are pipes, for the admission of a small quantity of water, which strikes against the under sides of the plates C and C', respectively, and is there broken, and falls as spray over the boulders H.

The result of their action is to keep the chambers above the boulders always full of spray and the boulders always wet, the water dripping from them, and thus carrying off the condensed impurities deposited on their surfaces by the passing gas.

C C' are circular reverberatory plates, made fast to the upper portion of the box M by the suspenders, v v, immediately underneath, and a short distance below, where the pipes A and A' empty into the box.

I is a chamber in the bottom of the box M, into which the water drips from the boulders, through the perforated bottom N, carrying the impurities deposited by condensation on them.

E is a pipe or siphon, through which the water, after having been used, is taken off from the box.

The shape shown in the drawing is not the best, in my opinion, for the purpose.

I prefer a pipe having a regular curve, without any sharp corners, such as are shown in the drawing.

K is a man-hole to the chamber I, through which the sediment deposited in it can be cleaned out.

The operation is as follows:

The gas enters the chamber L by the pipe A, from the retorts, striking against the upper surface of the reverberatory plate C, and is partially cooled by the action of the water on the under surface of said plate. There the resistance of the plate separates and spreads the gas through the chamber, and it descends down through the chamber, impelled forward by the force of the volume of gas entering from the retorts, and is in contact with the particles of spray descending from the plate C, and, by it, is considerably cooled by the time it reaches the boulders, through which it is forced down into the chamber I.

In its progress through the boulders, seeking as it will the route in which there is least resistance, the spaces between them being irregular, its course will be tortuous, and it will, in consequence, pass a large area of surface, kept constantly cool by the falling spray.

After the gas has passed through the chamber L into the chamber I, its only mode of exit will be into the chamber L', where it will enter and pass up through the boulders placed therein, and against the spray falling from the reverberatory plate C, and pass out of the pipe A'.

After the gas has passed through one box, such as here described, it may pass through others of the same kind, until it is in a fit state to pass through the dry lime.

Having thus described my invention, What I claim as new, and desired to secure by Letters Patent, is—

1. The surfaces of boulders, kept constantly wet, in the manner described, for the purpose described.
2. The pipe B, reverberating plate C, and the wet boulders, for the purpose described.

RICHARD SALTER.
